190,144

ROOF VENTILATOR

George M. Breidert, 11250 Zelzall Ave.,
Granada Hills, Calif.

Filed Apr. 19, 1960, Ser. No. 60,250

Term of patent 14 years

(Cl. D62—3)

Fig. 1 is a top view of a roof ventilator, showing my new design;

Fig. 2 is a bottom view;

Fig. 3 is a side view; and

Fig. 4 is a cross-sectional view taken on line 4—4 of Fig. 1 thereof.

The side not shown in the drawing is the same as the side shown in Fig. 3.

I claim:

The ornamental design for a roof ventilator, substantially as shown, and described.
